UNITED STATES PATENT OFFICE.

JOHN GRAMELSPACHER, OF JASPER, INDIANA.

DESIGN FOR A DESK.

SPECIFICATION forming part of Design No. 26,812, dated March 23, 1897.

Application filed February 4, 1897. Serial No. 622,056. Term of patent 7 years.

To all whom it may concern:

Be it known that I, JOHN GRAMELSPACHER, a citizen of the United States, residing at Jasper, in the county of Dubois and State of Indiana, have invented a new and original Design 5 for a Desk, (Case B,) of which the following is a specification.

This invention relates to a new and original design for a desk; and it has for its object to 10 provide a design of this character that shall be both useful and ornamental.

The leading feature of the design resides in a desk having a main flat rectangular table supporting a cabinet-top provided with quadrantal end pieces and a roll-curtain connecting the curved edges of said end pieces, a 15 drawer-holding pedestal arranged at one end of the main table and formed at its upper end with a squared cabinet portion extending the 20 full height and lying at one side of one of said quadrantal end pieces, said squared cabinet portion being provided with a rectangular front opening and a vertically-disposed roll-curtain connecting the vertical side edges of 25 said opening.

A minor feature of the design resides in combining with the features above enumerated an upright back portion for the cabinet-top of the main table, which back portion is 30 formed with a plurality of pigeonholes and a compartment in one upper corner of the back portion having a rectangular front door fitted in its front face with a correspondingly-shaped glass panel.

Another minor feature resides in forming 35 the upper squared cabinet portion of the drawer-holding pedestal with a plurality of interior rectangular compartments or pigeonholes, a horizontal flat shelf extending from the 40 lower tier of such compartments or pigeonholes to the front opening and with a flat forwardly-declining top board.

In the drawings, Figure 1 is a perspective 45 view of a desk embodying the herein-described design, showing the two roll-curtains thrown open. Fig. 2 is a similar view of the desk closed.

Referring to the accompanying drawings, the numeral 1 designates the main flat rectangular table of the desk supporting a cabinet-top having opposite quadrantal end pieces 2, a roll-curtain 3, connecting the curved edges of said end pieces, and an upright back portion formed with a plurality of pigeon-holes 4, and a compartment in one upper corner 50 having a rectangular front door 5, fitted in its front face with a correspondingly-shaped glass panel 6. Certain of the pigeonholes 4 are arranged in vertical columns extending 55 downward to the upper surface of the table 60 1 and inclosing a squared open space 7, in the upper corners of which space are arranged angular drawers 8 of a somewhat triangular form.

At one end of the main table 1 is arranged 65 a drawer-holding pedestal 9, receiving a plurality of rectangular drawers 10 and formed at its upper end with a squared cabinet portion 11. The squared cabinet portion 11 of the pedestal 9 extends the full height and lies 70 at one side of one of said quadrantal end pieces 2 and is provided with a flat forwardly-declining top board 12. The squared cabinet portion 11 is provided with a rectangular front opening 13, a plurality of interior rectangular compartments or pigeonholes 14, and a horizontal flat shelf 15, extending from the 75 lower tier of compartments or pigeonholes 14 to the front opening 13. A vertically-disposed roll-curtain 16 lies within the front 80 opening of the cabinet 11 and connects the vertical side edges of such opening.

What I claim is—

The design for a desk herein shown and described. 85

In testimony that I claim the foregoing as my own I have hereto affixed my signature in the presence of two witnesses.

JOHN GRAMELSPACHER.
